UNITED STATES PATENT OFFICE.

ALBERT H. GRAY, OF GRAND RAPIDS, MICHIGAN.

LAUNDRY APPLIANCE.

1,169,801.

Specification of Letters Patent.

Patented Feb. 1, 1916.

Application filed October 22, 1915. Serial No. 57,270.

To all whom it may concern:

Be it known that I, ALBERT H. GRAY, a citizen of the United States of America, residing at Grand Rapids, in the county of 5 Kent and State of Michigan, have invented certain new and useful Improvements in Laundry Appliances; and I do hereby declare the following to be a full, clear, and exact description of the invention, such as 10 will enable others skilled in the art to which it appertains to make and use the same.

This invention relates to a laundry appliance especially adapted for use in placing paper bags over suits of clothes or the like 15 after they have been cleaned in a laundry.

It is the object and purpose of my invention to provide a device of this character which may be utilized for placing a paper bag over a suit, dress or the like, irrespective 20 of the length thereof and in which this operation can be much more quickly and readily effected than heretofore. To this end I have provided the construction shown in the accompanying drawing, in which;

25 Figure 1 is a plan view; Fig. 2 a side elevation; and Fig. 3 an end elevation of the device.

Like reference characters refer to like parts throughout the several views of the 30 drawing.

In the construction of the appliance there is provided a board 1 of considerable length at each side of which thin upwardly projecting members 2 are attached, one end of 35 the board, hereafter termed the front end, being brought substantially to a point as indicated at 3 at which there is permanently secured a screw 4 having a closed eye positioned as and of the formation best shown 40 in Fig. 2. This board is supported a distance above the floor by the inclined supports 5 and 6 which cross each other, a pair of said supports being provided at each side and adjacent the rear end of the board and 45 connected at their upper ends by cross members 7 which are attached to the underside of the board 1.

A plurality of shelves 8, 9, 10 and 11 progressively decreasing in length are provided and located one above the other, being 50 supported and connected together by uprights 12 and 13, at each side of the shelves. The rear ends of each of the shelves, which are formed, preferably, of spaced apart slats or 55 the like, are connected by cross bars 14 which

rest against the front upper edges of supports 6, the structure as a whole being adapted to be secured to these supports by means of hooks 15 pivotally mounted on parts 6 and detachably connected with eyes 60 16 as shown. A bail is secured at the front ends of the shelves having depending legs 17 which are attached to the uprights 13, the upper ends of the legs being connected by an integral cross member 18 which lies 65 substantially in the same plane with the board 1 and a short distance in front thereof.

It will be noted that at various points on the board 1 indicating lines are drawn transversely thereof which are denoted by certain 70 numerals 30, 40, 50 and 60, indicating the length in inches from the front end of the board to this line. The shelves 8, 9, 10 and 11 in length are somewhat over 60, 50, 40 and 30 inches respectively, and on these 75 shelves paper bags of various lengths are placed.

In use, after a suit of clothes has been cleaned and pressed and placed on a garment hanger, the suit is laid on the board 1 lying 80 between the sides 2 and the hook of the garment hanger is passed through the eye of the member 4. If the lower end of the suit comes at about the line indicated by 40 a bag is taken from shelf 10 and placed over 85 the suit as it lies on the board, the bail with its upper cross member 18 serving to guide and hold the bag in proper position to easily pass it over the suit and the board. The bag is drawn until the member 4 with the hook 90 of the garment hanger therein punches through the bottom of the bag after which the hook of the garment hanger is disengaged from the eye and the suit of clothes with its covering bag thereon taken from the 95 device. For different lengths of suits bags from different shelves will be taken. For instance, a suit that is nearly 60 inches in length will be covered by a bag taken from the upper shelf 8.

Various changes in form and proportion of parts and in material of construction may be resorted to without departing from my invention which is defined in the appended claims.

I claim:

1. In a device of the character described, a flat horizontal member, means to support said member at one end thereof leaving the opposite end free to draw bags or the like 110

100

105

thereover, and means to support a bag adjacent said free end of the horizontal member and guide it as it is drawn over the member.

2. In a device of the character described, a flat horizontal member, means to support said member at one end thereof leaving the opposite end free and unobstructed, and a device having means to engage and hold the hook of a garment hanger secured at the free 10 end of the horizontal member.

3. In a device of the character described, a flat horizontal member, means to support said member at one end thereof leaving the opposite end free and unobstructed, a device 15 having means to engage and hold the hook on a garment hanger attached to the free end of the horizontal member, a horizontal bar located a distance from said free end of the member and in substantially the same horizontal plane, and means to support the bar 20 in said position.

4. In a device of the character described, a flat horizontal member, a support therefor at one end, a device having means for engaging 25 with the hook of a garment hanger secured at the opposite and free end of the member, a support below the horizontal member, and a bail secured to said support

having a horizontal portion positioned a distance from the free end of the horizontal 30 member and in substantially the same plane therewith.

5. In a device of the character described, a member, means to support said member at one end thereof leaving the opposite end free 35 and unobstructed, and a device having means to detachably engage and hold the hook of a garment hanger secured at the free end of the member, whereby bags may be drawn over said member and garments on a garment 40 hanger held by said device and thereafter removed from the member together with the garment and hanger.

6. In a device of the character described, a flat member located in substantially horizontal position, means to support said member at one end thereof leaving the opposite end free and unobstructed, and upwardly projecting members attached at each side 45 edge of said member to provide a place therebetween in which articles of wear may be positioned and serve as means to guide bags over said articles, substantially as described.

In testimony whereof I affix my signature. 55
ALBERT H. GRAY.
